2,494,366

PRODUCTION OF FATTY ESTERS

Francis J. Sprules, Arlington, N. J., and Donald Price, New York, N. Y., assignors to Nopco Chemical Company, Harrison, N. J., a corporation of New Jersey

No Drawing. Application July 15, 1947,
Serial No. 761,160

11 Claims. (Cl. 260—410.9)

1

This invention relates to the production of fatty esters and more particularly to an improved process for preparing alkyl esters of fatty acids.

From time immemorial soaps have been prepared by the saponification of fats and oils. The naturally occurring fatty materials are usually refined or purified and then intimately mixed with the proper proportions of alkaline agents and the mixture heated, thus forming soap and glycerine. The soap is then salted out of the mixture leaving an aqueous solution of glycerine, and the crude soap is given successive washings to recover any unseparated glycerine. Naturally there is a considerable loss of valuable fatty material as a consequence of the preliminary refining processes since the "foots" resulting therefrom are difficult to utilize. Also, processing equipment is tied up for long periods of time by the slow and cumbersome steps involved in both the refining and the soap manufacturing.

In recent years numerous uses for monohydric alcohol esters of fatty acids have been developed. For many purposes these esters are used as such and in other cases they are utilized as important intermediates in organic synthesis. Also, if desired, they may well be adapted to the production of high quality soaps.

By treating low grade fatty materials in accordance with the Twitchell process, or by complete saponification of the fatty materials in the crude state, the loss of valuable fatty material inherent in the conventional refining processes as mentioned hereinabove may be largely avoided. However, in order to convert the fatty acids in such crude fatty materials into commercially usable products, it is necessary to further treat the products obtained by either the Twitchell process or by complete saponification of the crude fatty material. For example, in the case of the Twitchell process, if it is desired to obtain alkyl esters of the fatty acids as the end product, the fatty acids must be dried and then esterified with a monohydric alcohol by means well known to those skilled in the art.

In the case of complete saponification of the crude fatty material, it is necessary to split the crude soaps with mineral acids, separate the fatty acids so liberated and then dry them before they can be converted to alkyl esters by conventional means.

It is distinctly desirable for economic reasons to convert a fatty glyceride directly to alkyl esters in a one-step process, particularly when these esters are to be used as such or as intermediates in organic syntheses. Thus it has been proposed

2

in recent years to react fatty materials with lower monohydric alcohols such as methanol or ethanol in the presence of catalyst to directly produce alkyl esters of the fatty acids. These alkyl esters can be used per se; saponified to produce high quality soaps; or used as intermediates in various organic syntheses. By such processes the foregoing and many other disadvantages inherent in the production of soap by the common methods of alkali-saponification of fatty materials are obviated. One of the most popular of these transesterification methods involves the use of an alkaline catalyst; however, when employing an alkaline transesterification process, relatively highly refined fatty materials, i. e., fatty materials having a low acid value, must be employed. The reason for this is that low grade materials which contain a large amount of free fatty acids must be neutralized before an alkaline catalyst will be effective. Neutralization of these acids produces a large amount of soap in the reaction mixture which greatly hampers the separation and recovery of both the ester and the glycerine. It also involves a considerable loss of fatty material.

Esterification processes utilizing an acidic catalyst usually require quite long reaction times and also give relatively low yields. An acidic catalyst is usually employed when treating fatty materials containing large amounts of free fatty acids; however, the yields of fatty ester are usually much less than the theoretical amount. Furthermore, the high acid content of the reaction mass considerably complicates the separation and purification of the fatty esters and the glycerine. Also, the products obtained are often of rather poor quality and must undergo various refining steps, thus adding to the cost of the process as well as further reducing the yield.

In order to eliminate the difficulties of the processes discussed above when treating fatty materials containing an appreciable proportion of free fatty acids, it has recently been proposed in U. S. Patent No. 2,383,601 to contact such a fatty material with an alcohol in the presence of an acidic esterification catalyst. After the esterification reaction has proceeded to a point where the free fatty acid content has been reduced to a tolerable or less proportion, an alkaline agent is added in an amount sufficient to neutralize the acid esterification catalyst and any free fatty acids still contained in the mixture, and to provide an excess of alkaline catalyst for an alcoholysis reaction which may then be carried out in any desired manner. It is claimed that this process will convert any free fatty acids to

alkyl esters prior to the alkaline esterification step, thus eliminating the use of large amounts of an alkaline catalyst and keeping the amount of soap formed down to a permissible amount where an alkaline alcoholysis can be rapidly and economically carried out without intermediate processing and without removal of esters or excess unreacted alcohol. This patented process results in a relatively low yield of alkyl esters. Furthermore, the resulting esters have a fairly high acid value which is a serious drawback tending to restrict the utility of the esters.

Industry has long felt the need for a process which could utilize low grade fats and oils for the production of high quality fatty esters without having to first refine the fatty materials, and which would produce yields of esters close to the theoretical amounts.

It is the object of this invention to provide an improved process for the production of fatty esters.

It is another object of this invention to provide a process for obtaining high yields of fatty esters from fatty materials.

A further object of this invention is to provide a process for obtaining high yields of fatty esters from high acid value oils.

Still a further object of this invention is to produce high quality fatty esters from high acid value oils.

Another object of the invention is to obtain fatty esters requiring little, if any, further refining from high acid value oils.

Other objects of the invention will in part be obvious and in part appear hereinafter.

We have discovered that the above and other objects of the invention may be realized by treating the desired fatty material with at least 2 moles of a primary or secondary alcohol per fatty acid equivalent, said alcohol containing up to 8 carbon atoms, in the presence of an alkaline esterification catalyst in sufficient amount to neutralize all the free fatty acids and to provide a slight excess for catalysis, heating the mixture for a short time, subsequently adding a mineral acid to the reaction mixture in sufficient amount to neutralize the alkali previously added and provide a slight excess, again heating the mixture and subsequently recovering the esters from the reaction mass.

The number of moles of alcohol per mole of glycerine or per equivalent of fatty acid contained therein depends on the acid value of the fatty raw materials, the alcohol to be used, and the operating conditions. When the reaction is carried out under reflux conditions and glycerides having very low acid values (1 to 6) are used, at least 2 to 3 moles of alcohol are required per fatty acid equivalent present. The lower figure is suitable for methanol and the higher figure for the other low molecular weight alcohols. In most cases we prefer to employ slightly larger amounts of alcohol, however, as better yields of esters are usually obtained thereby. For best results if fats of higher acid value are used, the mole ratio of alcohol to fatty acid equivalent should be raised; in the case of methanol, at least 4 moles should be used for each fatty acid equivalent in the raw material, and if almost any other low molecular weight alcohol is used, at least 8 moles of the alcohol should be used per fatty acid equivalent in the fatty material. The mole ratio of the alcohol to fatty acid equivalent can be lowered from the above figures when a fatty material having a high acid value is being treated by changing the

operating conditions. Instead of operating under reflux, the equilibria involved in the esterification steps can be favorably shifted by the continuous removal of the water formed; thus less of the alcohol is required to shift the equilibrium in favor of ester formation. Under these latter conditions when a fatty material having a high acid value is being treated, 5 moles of the alcohol is sufficient per fatty acid equivalent regardless of which alcohol is used and in some cases a ratio of 3 moles to one equivalent will suffice. The figure is dependent chiefly on the acid value of the fatty material to be used. As is well known, practically all commercial fatty materials have a positive acid value varying from 1 to 100 or more. Accordingly, the expression "fatty materials" is used herein to connote glyceride oils or fats having an acid value of at least one.

By this process very high yields of superior quality esters may be obtained from low quality fatty materials. Even fatty materials with acid values of over 100 are readily processed in accordance with our invention to give excellent yields of high quality fatty esters.

The invention accordingly comprises the several steps and the relation of one or more of such steps with respect to each of the others thereof, which will be exemplified in the process herein-after disclosed, and the scope of the invention 30 will be indicated in the claims.

In carrying out the process of our invention the fatty material is treated with a primary or secondary aliphatic alcohol containing up to 8 carbon atoms in the presence of an alkaline esterification catalyst. Sufficient catalyst is employed to neutralize any free fatty acids present and, in addition, provide an excess sufficient to catalyze the transesterification reaction. The reaction is preferably carried out by heating under 35 reflux, and a period of about one hour is ordinarily sufficient to complete the transesterification. The mixture, however, may be heated to any temperature desired to obtain any rate of alcoholysis. Furthermore, the transesterification 40 may be carried out in batch, intermittent, or continuous operation and at any desired pressure suitable for the reaction.

Following the alkaline-transesterification step 45 of our process, a mineral acid is added to the reaction mass in sufficient amount to neutralize the previously added alkaline material and to provide a slight excess. The addition of the acid hydrolyzes the soaps formed by the neutralization of the free fatty acid originally present in the 50 fatty material, thus providing a reaction mass containing alkyl esters, glycerine, free fatty acids, excess alcohol, acid esterification catalyst, and, in some cases, a small amount of unreacted glyceride. The free fatty acid and any unreacted 55 glyceride may now be esterified with the monohydric alcohol by heating the mass to any desired temperature in order to bring about a more rapid esterification. When using sulfuric acid as the esterification catalyst as in the preferred process of the invention, it is preferable 60 to add an amount of acid which will just neutralize the alkali and convert the excess sulfuric acid into sodium bisulfate in the reaction mass rather than using sufficient acid to give an appreciable quantity of free sulfuric acid in the 65 mass. The sodium bisulfate will serve very effectively as the acid catalyst. The acid esterification may be carried out in batch, intermittent, or continuous operation and at any suitable desired pressure. We prefer to heat the mixture 70

75

under reflux at atmospheric pressure in this step of the process.

When the esterification of the fatty material is completed, the reaction mass may separate into two layers with the upper layer containing alkyl esters and the lower layer containing the glycerine and excess alcohol. The two layers may then be separated by any suitable means and the esters and the glycerine each treated further to remove the acid catalyst, any entrained salts, alcohol, various impurities that may have been associated with the original fatty material, etc. The major amount of the excess alcohol will be in the glycerine layer and may be readily removed therefrom by a simple distillation, preferably after neutralization of the acid catalyst. In case the reaction mass does not separate into two layers upon completion of the esterification, the excess alcohol may be removed therefrom by distillation, preferably after neutralization of the acid catalyst. Upon removal of the excess alcohol the glycerine will separate from the esters, and then each may be treated further, if desired.

The process of our invention is applicable to the treatment of any fatty glyceride material; however, it is particularly applicable for the treatment of unrefined fats and oil, especially such materials having relatively high acid values. Excellent yields of high quality alkyl esters may be obtained from such fatty materials having acid values as high as 100 or more. Thus oils and fats such as corn oil, peanut oil, soybean oil, coconut oil, palm oil, cottonseed oil, olive oil, rice bran oil, foots resulting from the refining of these or other fatty materials, tallow, all types of fish oils, etc., may all be utilized in the process of our invention. In treating relatively hard oils and fats, e. g., hydrogenated oils and fats, it is preferred not to treat such fatty materials having acid values above 70 since the soaps formed by the alkali and the saturated fatty acids somewhat impede the efficiency of the alkaline trans-esterification step.

Among the alcohols which are applicable to the process of our invention are primary and secondary monohydric aliphatic alcohols having from 1 to 8 carbon atoms. When producing alkyl esters that are to be used for the subsequent production of soap, we prefer to employ either methanol or ethanol in the esterification steps; however, when the alkyl esters are to be later utilized as such or as intermediates in various organic syntheses, we vary the alcohol to obtain whatever alkyl ester may be desired. Among the alcohols suitable for the process of the invention are methanol, ethanol, propanol, butanol, amyl alcohol, fusel oil (a mixture of amyl alcohols), hexyl alcohol, heptyl alcohol, octyl alcohol, isopropanol, isobutanol, secondary butanol, 2 ethyl butanol, etc.

Any alkaline esterification catalyst such as metallic sodium, metallic potassium, sodium hydrox-

ide, sodium methylate, potassium hydroxide, potassium methylate, sodium amide, sodium hydride, potassium amide, potassium hydride, etc. may be used in the process of our invention.

- 5 In most cases it is preferred to use either the hydroxide or methylate of sodium. Among the acidic esterification catalysts suitable for the process of our invention are sulfuric acid, phosphoric acid, hydrochloric acid, organic sulfonic acids, trichloracetic acid, aluminum trichloride, alkyl sulfuric acids, etc. Usually, we prefer to employ either sulfuric or phosphoric acid as the catalyst in the acid esterification.

Not only does the process of our invention give very high yields of esters, but it also provides a means of obtaining high quality esters from low grade fatty materials.

For a fuller understanding of the nature and objects of our invention, reference may be had to the following examples which are given merely to further illustrate the invention and are not to be construed in a limiting sense:

Example I

- 25 880 grams (1 mole or 3 fatty acid equivalents) of hydrogenated fish oil (acid value 1.9) were refluxed for one hour with 480 grams (15 moles) of methanol in which 1% of sodium metal (based on weight of the oil) had previously been dissolved. Then 5% of sulfuric acid (based on the weight of the oil) was added and the reaction mass refluxed for four more hours. The reaction mixture was neutralized with calcium carbonate, filtered and freed of methanol by distillation. The ester layer was separated from the glycerine layer, the crude esters washed with warm water and then distilled under vacuum at a pressure of 1 mm. A 97% yield of high quality esters having an acid value of less than 1.0 resulted.

Example II

- 45 880 grams (1 mole or 3 fatty acid equivalents) of hydrogenated soybean oil (acid value 1.8) were refluxed with 375 grams (25 moles) of methanol in the presence of 1% of sodium methylate (based on the weight of the oil) for one hour. The reaction mixture was then further treated as in Example I except that 10% of phosphoric acid (based on the weight of the oil) was employed as the acid catalyst in place of the sulfuric acid, and the acid mass was refluxed for seven hours instead of for four hours as in Example I. A 96% yield of high quality esters having an acid value of less than 1.0 was obtained.

Example III

- 60 The process described in Example I was carried out using the ratio of fatty material to alcohol indicated below, the yield in each case being given:

	Fatty Material	Acid Value	Alcohol	Molar Ratio of Alcohol per Equivalent of Total Fatty Acid	Yield of Esters	Per cent
(1)	Hydrogenated Castor Oil.....	1.7	Methanol.....	8 to 1		86
(2)	Castor Oil.....	2.4	do.....	5 to 1		90
(3)	Hydrogenated Castor Oil.....	1.7	Ethanol.....	10 to 1		84
(4)	Hydrogenated Tallow.....	5.3	do.....	10 to 1		96
(5)	Hydrogenated Fish Oil.....	1.9	Isobutanol.....	10 to 1		89
(6)	Castor Oil.....	2.4	Butanol.....	10 to 1		90
(7)	Hydrogenated Soybean Oil.....	1.8	2-Ethyl-Butanol.....	10 to 1		97.5
(8)	Hydrogenated Fish Oil.....	1.9	Fusel Oil (mixed amyl alcohols).....	10 to 1		85

Example IV

The acid value of hydrogenated fish oil was raised by the addition of stearic acid to secure an oil blend having an acid value of 28.4. This oil blend was converted to methyl esters of the fatty acids by following the procedure outlined in U. S. Patent 2,383,601.

300 parts by weight (1.01 moles of fatty acid equivalent) of this hydrogenated fish oil blend were treated with 84 parts of methanol (2.63 moles) and 2.4 parts of concentrated sulfuric acid. The mixture was heated at the reflux temperature of methanol for one hour and 84 additional parts of methyl alcohol containing 5.0 parts of sodium hydroxide were introduced (thus giving a total mole ratio of alcohol to glyceride of 15.6/1 for the entire reaction). The mixture was again heated to the reflux temperature of the methanol and was stirred at this temperature for 45 minutes. The reaction mixture was then acidified with acetic acid and water-washed to neutrality. The crude esters were dried by the distillation of solvent and vacuum distilled at 1 mm. pressure. A 94% yield of distilled esters was obtained. However, these esters had an acid value of 18.3 thus indicating that a large percentage of the ester yield was actually free fatty acid.

Example V

880 parts by weight of hydrogenated fish oil having an acid value of over 29 were treated with 416 parts by weight of methanol (ratio of 13 moles of alcohol to 1 of oil). The reaction was carried out as set forth in Example I except that the mixture was refluxed for only half an hour in the alkaline transesterification step and for three hours in the acid esterification step. Also, 6% of sulfuric acid (based on the weight of the oil) was used instead of 5% as in Example I. A 96.6% yield of esters having an acid value of only 1.9 was obtained.

Example VI

860 parts by weight (1 mole) of melted tallow having an acid value of 7.5 were reacted with 480 parts by weight (15 moles) of methanol containing 1% of sodium hydroxide (based on the

gave a 99.5% yield of crude ester having an acid value of 1.6. This crude ester gave a 96.9% yield of distilled ester having an acid value less than 1.

Example VII

The acid values of several commercial oils were synthetically raised by the addition of free fatty acids. These oils were alkali-transesterified with methanol using as the alkaline catalyst 1% sodium hydroxide (based on the weight of the oil) in excess of the amount necessary to neutralize the free fatty acid, and refluxing for one hour. Sufficient sulfuric acid was then added to neutralize the alkali and provide an excess of 1% (based on the fatty material). After the acid mass was refluxed for four hours, it was allowed to stand, whereupon it separated into 2 layers. The upper layer was water-washed to neutrality, the crude esters dried and then vacuum-distilled. Excellent yields of high grade esters having very low acid values were obtained. The results are tabulated in the following table:

	Glyceride-Fatty Acid Mixture	Acid Value	Mole Ratio Alcohol/Fatty Acid Equivalent	Yield of Ester	Acid Value of Ester
25	Peanut Oil-Oleic Acid	94	15/1	Percent 94	1.4
30	Do	131	11/1	93.4	1.5
	Coconut Oil-Coconut Oil Fatty Acids	125	14/1	93.8	3.4

Example VIII

Several samples of rice bran foots were esterified with various alcohols by essentially the same process as that of Example VII. However, provision was made to dry the alcohol during the refluxing steps so that the water of reaction would not retard the process. In the first two cases, the water was separated mechanically in a Dean trap and dry alcohol was returned to the reaction vessel. In the next four cases, the alcohol azeotrope was removed from the reaction vessel by distillation through a short column and dried by refluxing with caustic soda pellets, and condensed dry alcohol was then returned to the reaction vessel. The results are shown in the following table:

Alcohol	Acid Value of the Rice Bran Foots	Mole Ratio Alcohol/Fatty Acid Equivalent	Reflux Time Alkali Step	Reflux Time Acid Step	Yield of Ester	Acid Value of Ester
2-Ethyl-Butyl	110	3.3/1	Hours 2	Hours 6	Percent 92.7	2.5
N-Butyl	100	5/1	1	6	94.0	3.7
Ethyl	104	5/1	2	2	88.0	3.0
Isopropyl	114	5/1	2	2	88.5	1.5
Isobutyl	104	5/1	2	3	97.3	1.4
Sec-Butyl	114	5/1	2	2	88.3	2.7

weight of the glyceride) by refluxing for two hours. After cooling somewhat, 3.5% of sulfuric acid (based on the weight of the glyceride) was slowly added and the mass refluxed for an additional four hours. The excess methanol was then removed by distillation, and the crude ester was separated from the reaction mixture and washed several times with hot water to remove the mineral acid. A 99.5% yield of crude ester having an acid value of 1.9 resulted. On distillation of the crude ester, a 94.5% yield of distilled ester having an acid value of 1.0 was obtained.

A similar treatment of another sample of the tallow using potassium hydroxide as the alkaline catalyst in place of the sodium hydroxide

In the claims when we refer to neutralizing the alkaline catalyst following the transesterification step, we use the word "neutralize" in its broad sense as meaning overcoming the effect of the alkaline catalyst and giving the reaction mixture a neutral pH. Thus, for example, if sulfuric or phosphoric acid is used as the acid catalyst and sodium hydroxide is the alkaline catalyst, the end product of complete neutralization of the alkali will be an acid salt and the resulting solution instead of being neutral will be slightly acid. However, if hydrochloric acid is employed as the acid catalyst, the end product of complete neutralization of the alkali will be a neutral salt and the resulting solution will also be neutral.

Consequently, we use the word "neutralize" in the claims when speaking of neutralizing the alkaline catalyst to mean that sufficient acid catalyst is added to the alkaline reaction mixture to give the mixture approximately a neutral pH. Then after neutralizing the alkaline catalyst in that sense, we add an additional amount of acid catalyst so as to provide sufficient acidic material to act as an acid catalyst. If hydrochloric acid is used as the acid catalyst, that acidic material will, of course, be free hydrochloric acid; but if the acid is either phosphoric or sulfuric acid, the acidic material will be an acid salt, e. g., sodium acid sulfate, and if sufficient excess acid is added, there will also be some free acid present. However, as pointed out hereinabove, when sulfuric acid is employed, if all of the alkali originally added is converted to sodium acid sulfate, there will be sufficient acidic material present to catalyze the esterification without adding additional sulfuric acid so as to have free sulfuric acid present.

Having described our invention, what we claim as new and desire to secure by Letters Patent is:

1. In a process for producing alkyl esters of fatty acids, the steps comprising transesterifying fatty materials having acid values of at least one by contacting said fatty materials with at least two moles of a monohydric alcohol per fatty acid equivalent, said monohydric alcohol containing from one to eight carbon atoms, in the presence of a sufficient amount of an alkaline catalyst to neutralize the free fatty acids in the fatty material and provide a slight excess of alkaline material to serve as the transesterification catalyst, heating the mass for a short time to effect transesterification, adding a sufficient amount of an acid catalyst to split the soaps in the reaction mass, neutralize the alkaline catalyst in the reaction mass, and provide a slight excess of acidic material to serve as an esterification catalyst, and then esterifying the free fatty acids in the reaction mass with the monohydric alcohol present therein by further heating of the mass.

2. In a process for producing alkyl esters of fatty acids, the steps comprising transesterifying fatty materials having acid values of at least one by contacting said fatty materials with at least three moles of a monohydric alcohol per fatty acid equivalent, said monohydric alcohol containing from one to eight carbon atoms, in the presence of a sufficient amount of an alkaline catalyst to neutralize the free fatty acids in the fatty material and provide a slight excess of alkaline material to serve as the transesterification catalyst, heating the mass at about the reflux temperature of the alcohol for a short time to effect transesterification, adding a sufficient amount of an acid catalyst to split the soaps in the reaction mass, neutralize the alkaline catalyst in the reaction mass, and provide a slight excess of acidic material to serve as an esterification catalyst, and then esterifying the free fatty acids in the reaction mass with the monohydric alcohol present therein by further heating of the mass at about the reflux temperature of the alcohol.

3. In a process for producing alkyl esters of fatty acids, the steps comprising transesterifying a fatty material having an acid value of at least one by contacting said fatty material with at least two moles of methanol per fatty acid equivalent in the presence of a sufficient amount of an alkaline catalyst to neutralize the free fatty

acids in the fatty material and provide a slight excess of alkaline material to serve as the transesterification catalyst, heating the mass at about the reflux temperature of the alcohol for a short time to effect transesterification, adding a sufficient amount of an acid esterification catalyst to split the soaps in the reaction mass, neutralize the alkaline catalyst in the reaction mass, and provide a slight excess of acidic material to serve as an esterification catalyst, and then esterifying the free fatty acids in the reaction mass with the methanol present therein by further heating of the mass at about the reflux temperature of the alcohol.

4. In a process for producing alkyl esters of fatty acids, the steps comprising transesterifying a fatty material having an acid value of at least one by contacting said fatty material with at least two moles of butanol per fatty acid equivalent in the presence of a sufficient amount of an alkaline catalyst to neutralize the free fatty acids in the fatty material and provide a slight excess of alkaline material to serve as the transesterification catalyst, heating the mass at about the reflux temperature of the alcohol for a short time to effect transesterification, adding a sufficient amount of an acid esterification catalyst to split the soaps in the reaction mass, neutralize the alkaline catalyst in the reaction mass, and provide a slight excess of acidic material to serve as an esterification catalyst, and then esterifying the free fatty acids in the reaction mass with the butanol present therein by further heating of the mass at about the reflux temperature of the alcohol.

5. In a process for producing alkyl esters of fatty acids, the steps comprising transesterifying fatty materials having acid values of at least one by contacting said fatty materials with at least two moles of a monohydric alcohol per fatty acid equivalent, said monohydric alcohol containing from one to eight carbon atoms, in the presence of a sufficient amount of an alkaline catalyst to neutralize the free fatty acids in the fatty material and provide a slight excess of alkaline material to serve as the transesterification catalyst, heating the mass at about the reflux temperature of the alcohol for a short time to effect transesterification, adding a sufficient amount of sulfuric acid to split the soaps in the reaction mass, neutralize the alkaline catalyst in the reaction mass, and provide a slight excess of acidic material to serve as an esterification catalyst, and then esterifying the free fatty acids in the reaction mass with the monohydric alcohol present therein by further heating of the mass at about the reflux temperature of the alcohol.

6. In a process for producing alkyl esters of fatty acids, the steps comprising transesterifying fatty materials having acid values of at least one by contacting said materials with at least two moles of a monohydric alcohol per fatty acid equivalent, said monohydric alcohol containing from one to eight carbon atoms, in the presence of a sufficient amount of sodium hydroxide to neutralize the free fatty acids in the fatty material and provide a slight excess of alkaline material to serve as the transesterification catalyst, heating the mass at about the reflux temperature of the alcohol for a short time to effect transesterification, adding a sufficient amount of an acid catalyst to split the soaps in the reaction mass, neutralize the alkaline catalyst in the reaction mass, and provide a slight excess of acidic ma-

11

terial to serve as an esterification catalyst, and then esterifying the free fatty acids in the reaction mass with the monohydric alcohol present therein by further heating of the mass at about the reflux temperature of the alcohol.

7. In a process for producing alkyl esters of fatty acids, the steps comprising transesterifying fatty materials having acid values of at least one by contacting said fatty materials with at least two moles of a monohydric alcohol per fatty acid equivalent, said monohydric alcohol containing from one to eight carbon atoms, in the presence of a sufficient amount of an alkaline catalyst to neutralize the free fatty acids in the fatty material and provide a slight excess of alkaline material to serve as the transesterification catalyst, heating the mass at about the reflux temperature of the alcohol for a short time to effect transesterification, adding a sufficient amount of phosphoric acid to split the soaps in the reaction mass, neutralize the alkaline catalyst in the reaction mass, and provide a slight excess of acidic material to serve as an esterification catalyst, and then esterifying the free fatty acids in the reaction mass with the monohydric alcohol present therein by further heating of the mass at about the reflux temperature of the alcohol.

8. In a process for producing alkyl esters of fatty acids, the steps comprising transesterifying fatty materials having acid values of at least one by contacting said materials with at least two moles of a monohydric alcohol per fatty acid equivalent, said monohydric alcohol containing from one to eight carbon atoms, in the presence of a sufficient amount of sodium hydroxide to neutralize the free fatty acids in the fatty material and provide a slight excess of alkaline material to serve as the transesterification catalyst, heating the mass at about the reflux temperature of the alcohol for a short time to effect transesterification, adding a sufficient amount of sulfuric acid to split the soaps in the reaction mass, neutralize the sodium hydroxide in the reaction mass, and provide a slight excess of acidic material to serve as an esterification catalyst, and then esterifying the free fatty acids in the reaction mass with the alcohol present therein by further heating of the mass at about the reflux temperature of the alcohol.

9. In a process for producing alkyl esters of fatty acids, the steps comprising transesterifying fatty materials having acid values of at least one by contacting said materials with at least two moles of a monohydric alcohol per fatty acid equivalent, said monohydric alcohol containing from one to eight carbon atoms, in the presence of a sufficient amount of sodium hydroxide to neutralize the free fatty acids in the fatty material and provide a slight excess of alkaline material to serve as the transesterification catalyst, heating the mass at about the reflux temperature of the

12

alcohol for a short time to effect transesterification, adding a sufficient amount of phosphoric acid to split the soaps in the reaction mass, neutralize the sodium hydroxide in the reaction mass, and provide a slight excess of acidic material to serve as an esterification catalyst, and then esterifying the free fatty acids in the reaction mass with the alcohol present therein by further heating of the mass at about the reflux temperature of the alcohol.

10. In a process for producing alkyl esters of fatty acids, the steps comprising transesterifying fatty materials having acid values of at least one by contacting said fatty materials with at least two moles of methanol per fatty acid equivalent in the presence of a sufficient amount of sodium hydroxide to neutralize the free fatty acids in the fatty material and provide a slight excess of alkaline material to serve as the transesterification catalyst, heating the mass at about the reflux temperature of the alcohol for a short time to effect transesterification, adding a sufficient amount of sulfuric acid to split the soaps in the reaction mass, neutralize the sodium hydroxide in the reaction mass, and in addition provide a slight excess of acidic material to serve as an esterification catalyst, and then esterifying the free fatty acids in the reaction mass with the methanol present therein by further heating of the mass at about the reflux temperature of the alcohol.

11. In a process for producing alkyl esters of fatty acids, the steps comprising transesterifying fatty materials having acid values of at least one by contacting said fatty materials with at least two moles of butanol per fatty acid equivalent in the presence of a sufficient amount of sodium hydroxide to neutralize the free fatty acids in the fatty material and provide a slight excess of alkaline material to serve as the transesterification catalyst, heating the mass at about the reflux temperature of the alcohol for a short time to effect transesterification, adding a sufficient amount of sulfuric acid to split the soaps in the reaction mass, neutralize the sodium hydroxide in the reaction mass, and provide a slight excess of acidic material to serve as an esterification catalyst, and then esterifying the free fatty acids in the reaction mass with the butanol present therein by further heating of the mass at about the reflux temperature of the alcohol.
